UNITED STATES PATENT OFFICE.

CHRISTIAN F. PAUL, JR., OF PEEKSKILL, NEW YORK, ASSIGNOR TO THE PAUL & KREUGER ROCK DRILL COMPANY, A CORPORATION OF NEW YORK.

HAND ROCK-DRILL.

No. 878,152.

Specification of Letters Patent.

Patented Feb. 4, 1908.

Application filed June 21, 1906. Serial No. 322,669.

To all whom it may concern:

Be it known that I, CHRISTIAN F. PAUL, Jr., a citizen of the United States, and resident of Peekskill, in the county of West-
chester and State of New York, have invented certain new and useful Hand Rock-Drills, of which the following is a specification.

This invention relates to rock drilling, and its object is to provide an efficient hand-operating machine for that purpose, which object is attained by the means set forth in these specifications and the accompanying drawings, in which like letters refer to similar parts throughout the several views.

Figure 1, Sheet 1, is a perspective view of the machine. Fig. 2 is a plan of the machine. Fig. 3 shows the tripod swivel attachment. Fig. 4 shows the tripod swivel clamp. Fig. 5 is a top view of the drill rotator. Fig. 6 is explanatory of Fig. 5. Fig. 7, Sheet 2, illustrates the action of the yoke. Fig. 8 is explanatory of a quick-stroke gearing. Fig. 9 is a side, partly sectional, view of the box A and the mechanism therein. Fig. 10 illustrates the movable crank-pin. Fig. 11 shows the crank-disk without the crank-pin. Fig. 13 is an edge view of the crank disk. Fig. 14 is a side view of the parts *i*, *j*, Figs. 10 and 11. Fig. 15 is an inside edge view of the parts *i*, *j*. Fig. 16 illustrates the action of the movable crank-pin.

The machine as shown in Fig. 1, on tripod supports 38, comprises a box or casing A that contains the operating devices, and has grooves 10 10 on its sides, adapting it to slide on the guide rails 11 11, which are held together by cross-bars 12 12 and the plates 13 in the center. The upper cross-bar supports a nut 14 threaded for the screw 15. A nut 14', Fig. 3, on the under side of the box receives said screw, and by means of a crank 16, Fig. 1, on the screw, the box is moved upon the rails.

The swivel attaching the box A to the tripod is shown in Fig. 3. A disk 17 has an offset flange on its periphery, as in Fig. 4, the plates 13 13 have reverse recesses to receive the disk, as at 13'. The larger rim of the disk lies next the rails 11, and tightening the bolts 18, 18, draws the plates together and holds the machine from turning. The lugs 20 20 are integral with the disk, and supports a shaft *k* for the tripod legs.

The interior of the machine is disclosed in Figs. 2 and 9. A disk *g* revolving on a shaft

c has a crank-pin *p* engaging with a yoke *y*. A block *f* affords a bearing for the crank-pin and travels in the curved slot in the yoke. The vertical slot *y'* in the yoke incloses the shafts *e* *e'*, and the shafts guide the vertical movement of the yoke.

The machine is driven by a crank 19, Fig. 1, on the shaft *e* (or it may be driven by a motor). Fig. 9 shows the transmission of motion from the crank to the yoke. The shaft *e* is fast in the wheel *m''*. The pinion *m'* and wheel *m* are fast on shaft *e'*. The pinion *m'* and disk *g* are secured together and revolve on shaft *e*. The two shafts have bearings *l* *l'* in the box A. The gears are proportioned to give the disk five revolutions to one of the crank.

The action of the yoke *y* is shown in Fig. 7, where it is seen ready for a downward stroke. The curved slot in the yoke is a quadrant, and pitched in relation to its vertical movement, so that radii from its curves will meet in a center in a vertical plane with the center of the crank-pin when at the position *d*. As the crank-pin moves from the position at *a* to the position at *b* the yoke will move from *a'* to *b'*, which exceeds the crank movement by the distance from *b'* to *c'*. As the crank-pin moves from the position at *b* it begins to lift the yoke, and in completing the quarter-stroke from *b* to *c* will lift the yoke from *b'* to *c'*. Through the next quarter-revolution the yoke will be lifted from *c'* to *d'*, and in the next quarter from *d'* to *a'*. Thus, through three-quarters of its revolution the crank-pin will lift the yoke, and through its last quarter will precipitate the yoke quickly the full length of its down stroke: a movement representing the slow lifting of a hammer and its quick throwing down. Fig. 2 shows the yoke at the end of its down stroke.

Especial advantages are derived from the gearing shown in Figs. 2 8 and 9. Referring to Fig. 8, the pinion *m'* is eccentric to its shaft, and the driver *m* is adapted to engage with the pinion and to give to it three revolutions to one of the wheel, the wheel accordingly having three elliptical divisions. From one high point to the next high point, or vice versa, causes a revolution of the pinion. When the wheels are in the position shown the pinion, following the arrows, is entering its period of maximum velocity. Simultaneously the crank-pin is at *a*, and during the rapid movement of the pinion the crank-

pin will be moved from *a* to *b*, which is during the descent of the yoke. While lifting the yoke the short axes of the wheel will engage with the long axes of the pinion, thus easing the lifting operation. The objects and effects of the gearing are to facilitate the lifting of the yoke, to accelerate its precipitation, and make a steadier pull upon the hand-crank.

Evidently, an obstruction of the full down-stroke of the yoke might result in a re-action injurious to the machine. To avoid this the crank-pin is adapted to move towards the center of the disk, as shown in Figs. 10 to 15, inclusive. In Fig. 10 the crank-pin *p* is shown as secured in a block *h* that moves on **V** guides 1 1 in a slot in the disk. Fig. 12 shows the block in perspective. The slot has a closure *i*, *j*, held in place by screws 8 8, Fig. 11. Fig. 13 is an edge view of the disk without the closure or block, and Figs. 14 15 show the form of the closure. Springs 6 6 in recesses 3 3 in the disk, Fig. 11 keep the block in normal position as shown in Figs. 2, 10 and 16.

Fig. 16 illustrates what would occur if the yoke failed to complete a down-stroke, by reason of the drill getting fast, or other cause.

Fig. 7 shows that while the yoke is descending the travel of the block *f* is about perpendicular, which allows the block a little liberty of movement, at the end of which, if the yoke does not rise at once, the block *h* moves centerward of the disk, as in Fig. 16. If the line *x* should indicate the end of the stroke, but it had stopped at *x'*, the block *h* would move from the broken line *x''* to the solid line *x'''*, and would begin to lift the yoke, and if the movement of the block did not overcome the resistance of the drill the yoke would still move by reason of the yielding connection of the yoke with the drill spindle. If this giving of the two yielding parts did not release the drill, the machine would come to a stop without shock or injury.

The yoke has a spindle terminal *y'*, Figs. 2 and 9 with a head *s''* at its extremity. The drill spindle *n'* has a bore in its upper end to receive the spindle *y'* and a spring *s'* that surrounds the spindle. A bushing *r* in the bore compresses the spring between the bushing and the head *s''*. If the drill does not promptly respond to the lifting of the yoke the head *s''* is lifted against the spring, and the machine is relieved from sudden shock.

The tube projection *n* on the box *A* affords a bearing for the drill spindle *n'*, and contains means for rotating the drill-spindle. The inner diameter of the tube is larger than the drill-spindle, the lower outlet being adapted to the spindle by a bushing *o*, Figs. 2 and 9. On the drill-spindle is a collar *s*, Fig. 9, having rollers *u* on its face, shown in plan in Fig. 5. On the inner surface of the tube are 65 cam-grooves in which the said rollers travel.

Fig. 6 represents the tube opened out showing the formation of the grooves. The circles within the grooves represent the changing positions of the rollers, and the broken lines the paths of the rollers. At 50 the roller is on a downward stroke; the point *w* of the projecting surface *w* will cause it to move to the groove 51. On the return stroke the point *v* of the projecting surface *v* will divert the roller to the groove 52, so that with every 75 complete stroke of the yoke the rollers advance from one upper groove to the next one, the drill making a complete revolution with every five strokes.

Except in the application of power to the 80 machine, it is to be handled the same as the ordinary rock-drills.

Having described my invention, what I claim and desire to secure by Letters Patent, is—

1. In a hand rock drill the combination of 85 a curved yoke for imparting a reciprocating motion to the drill, and a variable speed gearing for operating the yoke comprising an eccentric wheel and a wheel adapted to engage with the eccentric wheel for driving the same.

2. In a hand rock drill the combination with a yoke for imparting a reciprocating motion to the drill, of a crank for giving 95 motion to the yoke, said crank having a movable crank-pin comprising a crank disk, a slot in the disk, a movable block in said slot, the crank-pin secured in the movable block, and springs bearing against the block to retain it in its normal position in the slot.

3. In a hand rock drill the combination with a yoke for imparting a reciprocating motion to the drill, of the drill spindle swiveled to the end of the yoke, and a spring 105 within the drill-spindle acting upon the yoke-spindle to elastically keep the yoke-spindle seated in the drill-spindle.

4. The combination in a rock drill of a yoke for imparting a reciprocating motion to 110 the drill, the yoke having a quadrant shaped slot for the crank connection, the slot pitched from a horizontal so that radii from its curves will meet in a center in a vertical plane with the center of the crank-pin when the 115 crankpin is at its left center, and a variable gear for operating the same comprising an eccentric pinion fast to the crank-disk, and a driving wheel adapted to engage with the eccentric pinion.

5. In a rock drill, in a crank for imparting a reciprocating motion to the drill, a movable crank-pin comprising a crank-disk a slot in the crank-disk, a movable block in said slot, the crank-pin secured in said block, and 125 springs bearing against the block to retain it in its normal position.

6. In a rock drill the combination of a curved yoke for giving motion to the drill, a yielding crank-pin in the crank operating the 130

yoke, and an elastically swiveled connection between the yoke and the drill spindle.

7. In a rock drill the combination with a curved yoke and a crank for imparting motion to the drill, gearing for transmitting motion from the hand crank to the yoke comprising in the train an eccentric wheel, a driving wheel adapted to engage with the eccentric wheel, a yielding crank-pin in the 10 yoke driving crank and a swiveled yielding

connection of the yoke with the drill spindle, and means for rotating the drill.

Signed at Peekskill in the county of Westchester and State of New York this 16th day of June A. D. 1906.
